UNITED STATES PATENT OFFICE.

EDGAR M. MOORE, OF PITTSBURGH, PENNSYLVANIA.

HYDRANT.

1,265,479.

Specification of Letters Patent.

Patented May 7, 1918.

Application filed August 23, 1917. Serial No. 187,797.

To all whom it may concern:

Be it known that I, EDGAR M. MOORE, a resident of Pittsburgh, in the county of Allegheny and State of Pennsylvania, have 5 invented a new and useful Improvement in Hydrants; and I do hereby declare the following to be a full, clear, and exact description thereof.

This invention relates to automatic cut-off hydrants, and more particularly to a hydrant of this class that will utilize the pressure of the fluid passing therethrough to operate the cut-off mechanism.

The principal objects of the invention are 15 to provide a hydrant that will eliminate the necessity of cut-off valves in pipe lines, and to generally improve the art of hydrants and spigots or faucets by providing means for the escape of water above the valve and 20 other novel details of structure which will be more fully brought out in the specification.

In the drawings I have shown one preferred embodiment of my invention, but it 25 will be understood that various changes in structure and design may be made by a mechanic skilled in the art to which this invention belongs without departing from the spirit of my invention as defined in the 30 appended claims.

In the drawings,

Figure 1 is a vertical sectional view through a hydrant constructed according to my invention;

35 Fig. 2 is a detail view showing the construction of the cut-off mechanism; and

Fig. 3 is a top plan view of the cut-off valve.

Referring more particularly to the drawings, the numeral 2 designates the main casing of my hydrant having a screw top 40 portion 3 of ordinary construction and having the usual inlet and outlet portions 4 and 5 respectively.

45 The valve portion of the hydrant comprises a post member 6 of variable diameters decreasing toward the lower end. Mounted on the post as at 7 are a plurality of circular members 8 having apertures 50 therein and being preferably of spider construction. There are preferably provided three of the members 8 and mounted between the members and held in place by the clamping action thereof are washers 9

adapted to frictionally engage the inside 55 face of casing 2.

Mounted below and abutting the members 8 is a valve member 10 having a valve face 11 adapted to seat on the valve seat 12 formed around the inner circumference of 60 the casing 2. Suitable locking or securing means such as a washer or ring 13 and nut 14 are provided for holding the valve member in place.

Adjacent the lower end of the casing 65 member is an inwardly extending flange 15 adapted to normally support a valve member 16 having a tubular downwardly extending stem 17 having a closed lower end and an open upper end. The post 6 has its 70 lower end inserted in the tubular stem 17 and is adapted to freely rotate therein. The under side of the valve seat 12 is beveled forming a seat 18 for the valve 16.

When the valve member 10 is closed the 75 post or stem 6 will force said valve 16 downwardly into tight engagement with the shoulder or flange 15, thereby providing an auxiliary or extra cut-off for the main water supply, preventing pressure against 80 the flexible face 11 of the valve 16.

The casing 2 has small apertures or drain 85 exits 19 on its end spaced above the valve seat 12 a sufficient distance so as to be open when the valve 10 is seated and to be closed by the valve 10 when it is raised or unseated. It will thus be seen that any liquid remaining above the valve 10 after it is seated will 90 escape through the exits 19 and prevent freezing.

A screw threaded operating stem 20 of well known construction is revolvably mounted in the upper portion of the casing and passes through a suitable stuffing box 21. The stem 20 has its lowered end squared as 95 at 22 to loosely engage a socket 23 in the upper end of the post 6, and is provided on its upper end with an operating wheel 24.

The operation of my device is as follows: Liquid under pressure enters the inlet 4 100 and is stopped by the valve member 16. To cause the liquid to flow through my hydrant, the stem 20 is rotated by the hand wheel 24 thereby allowing post 6 to rise within the casing 2. As the post rises within the casing 105 2, the pressure of the liquid will force the valve 16 upwardly thereby allowing a passageway around said valve for the liquid so

that it may force upwardly against the valve 10, thereby unseating said valve and allowing a continuous flow of liquid upwardly through the spider formed members 8 and 5 outwardly through the outlet portion 5 of my hydrant.

Provided that the valve members or washers 12 or 9 or any other portion of the post 9 becomes worn or broken, the top portion of 10 the hydrant may be disassembled and the post removed without in any manner shutting off the pressure of the liquid. However, the liquid will not flow through the disassembled hydrant for the reason that the 15 valve 16 or automatic cut-off would be forced by the pressure of liquid upwardly against the valve seat 18 thereby preventing any further flow of the liquid.

Although I have shown and described my 20 improvements as pertaining to hydrants, it will be readily seen that they may be applied to the ordinary form of spigot or faucet, and I wish it expressly understood that such application of my improvements is within the 25 scope of the appended claims.

Having thus described my invention, what I claim is:—

- 30 1. In combination with a casing having a valve stem and valve therein, and an automatic cut-off valve loosely mounted in the lower end thereof adapted to be seated by the pressure of liquid within said casing when said valve stem is removed and to be normally held open by said valve stem, said 35 cut-off comprising a valve member provided with a tubular stem having a closed bottom end and an open upper end and said stem being adapted to receive the lower end of said valve stem.
- 40 2. A hydrant of the class described com-

prising a casing, a vertically movable main valve stem mounted within said casing, a valve on said stem, said main valve stem projecting below said valve an appreciable distance, and an automatic cut-off valve loosely 45 mounted in the lower end of said casing and comprising a valve member provided with a downwardly projecting tubular stem portion having a closed bottom, said projecting portion of said main valve stem being adapted 50 to fit within said tubular stem of said last-named valve to guide and control the movement thereof.

3. A hydrant of the class described, comprising a casing, a vertically movable main 55 valve stem mounted within said casing, a valve on said stem, said main valve stem projecting below said valve an appreciable distance, and an automatic cut-off valve loosely mounted in the lower end of said casing and comprising a valve member provided with a downwardly projecting tubular stem portion having a closed bottom, said 60 projecting portion of said main valve stem being adapted to fit within said tubular stem 65 of said last named valve to guide and control the movement thereof, a seat formed within said casing against which said cut-off valve is adapted to seat when said main valve is withdrawn from said casing, and an inwardly extending flange at the lower end 70 of said casing against which said valve is adapted to seat when said main valve is closed.

In testimony whereof, I the said EDGAR 75 M. MOORE have hereunto set my hand.

EDGAR M. MOORE.
